UNITED STATES PATENT OFFICE.

FRANK J. HERRICK, OF NEW BRITAIN, CONNECTICUT, ASSIGNOR TO THE NORTH & JUDD MANUFACTURING COMPANY, OF SAME PLACE.

HORSE-BLANKET BUCKLE.

SPECIFICATION forming part of Letters Patent No. 499,458, dated June 13, 1893.

Application filed January 5, 1893. Serial No. 457,389. (No model.)

To all whom it may concern:

Be it known that I, FRANK J. HERRICK, a citizen of the United States, residing at New Britain, in the county of Hartford and State 5 of Connecticut, have invented certain new and useful Improvements in Blanket-Buckles, of which the following is a specification.

My invention relates to improvements in blanket buckles; and the objects of my improvement are simplicity of construction and general efficiency and convenience in operation.

In the accompanying drawings, Figure 1 is a front elevation of my buckle as applied to a strap and portion of a blanket. Fig. 2 is a vertical section of said buckle on the line *x* *x* of Fig. 1. Fig. 3 is a horizontal section on the line *y* *y* of Fig. 1. Fig. 4 is a rear elevation of the principal part, and Fig. 5 is a front 20 elevation of the fastening head.

A designates the blanket, and B, the strap secured thereto in connection with my buckle. The principal part of the buckle is provided with end loops 6 6 for the passage of the strap 25 in securing the same to the blanket, which loops are connected by a middle portion in the form of curved side bars 7 7. The space between the side bars is widest toward their upper end so as to form a narrow slot or space 30 between the lower end of the side bars as shown. At the rear of the principal part, I secure a spring 8. The other part of the buckle is a fastening head provided with a loop 9 for the attachment of the free end of 35 the strap B, and a projecting button like tongue 10, which is largest near its upper end, said tongue projecting from the loop 9 at the middle of the upper cross bar of the loop and in the same general direction as the plain of 40 said loop. At the junction of said tongue and loop I form a forwardly projecting lug 11 for a finger piece.

The end of the strap B containing the buckle proper is sewed securely to the blanket, 45 while the end containing the fastening head is the free end of the strap. The greatest diameter of the head 10 is wider than the space between the side bars, so that when the parts are in the position shown in Figs. 1, 2 50 and 3 they are securely held against accidental detachment. The curve of the side bars

enables the button like tongue to come upon the inside of said bars while the finger piece 11 is upon the outside. In order to detach or unfasten the parts, the thumb or finger is 55 pressed upwardly on the lug 11 to push the fastening head 9 upwardly between the side bars carrying the button like end of the tongue 10 over the bearing point of the spring 8 to the wider part of the opening near the 60 upper end of the side bars, when the head may be pulled forward and detached. In order to attach the parts again, it is only necessary to draw up the free end of the strap and insert the button like end of the tongue 65 10 between the upper ends of the side bars and then pull it downwardly into place as shown.

While I prefer to employ the spring 8, it is evident that in some positions an efficient buckle would be formed without the employment of said spring, the other parts being precisely the same as herein shown. While I have described the buckle as arranged up and down on the blanket, it is of course evident that the construction would be the same 75 if the buckle were used in a horizontal position.

By my improvement, I not only produce a cheap and efficient buckle, but by the employment of the lug 11 the head may be pushed 80 upwardly with the thumb or finger for detaching the parts, the construction shown permitting this lug 11 to be employed. The general form of the principal part of my buckle, consisting of the end eyes 6 6, the 85 side bars 7 and the spring at the rear is shown and described in another application filed by me and this application is made subordinate thereto.

I claim as my invention—

1. The herein described buckle consisting of the principal part with the space between the side bars 7 contracted toward the lower end, and the fastening head 9 provided with a button like tongue 10 adapted to engage 95 said side bars on one side of said principal part and also provided with the finger piece 11, located on the opposite side of said bars from said button like tongue when said principal part and head are engaged substantially 100 as described and for the purpose specified.

2. The herein described buckle consisting

- of the frame having the curved side bars 7 7 with the space between them contracted at the lower ends, and the head 9 consisting of the loop 11 and central button like tongue 5 projecting from the middle portion of the upper cross bar of said loop in substantially the same general direction as the plane of said loop substantially as described and for the purpose specified.
- 10 3. The herein described buckle consisting of the frame having the side bars 7, 7, with the space between them contracted at the lower end, the head 9, provided with a central

button like tongue for detaching and attaching it to and from said side bars and a spring 15 arranged between said side bars with one portion back of the button portion of said tongue and another portion lying partially in front of the end of said tongue when the parts are secured together, substantially as described 20 and for the purpose specified.

FRANK J. HERRICK.
